United States Patent Office

Des. 202,383
Patented Sept. 21, 1965

202,383

DECANTER AND CLOSURE THEREFOR

Ernest L. Du Pree, New York, N.Y., assignor to Schenley Industries, Inc., New York, N.Y., a corporation of Delaware

Filed July 14, 1964, Ser. No. 80,864

Term of patent 14 years

(Cl. D58—6)

Fig. 2

Fig. 1

Fig. 7

Fig. 8

Fig. 9

FIGURE 1 is a front elevational view of a decanter and closure therefor embodying my new design;

FIGURE 2 is a side elevational view thereof with the closure removed;

FIGURE 3 is a rear elevational view thereof;

FIGURE 4 is a sectional view, taken on the line 4—4 of FIGURE 3;

FIGURE 5 is a sectional view, taken on the line 5—5 of FIGURE 3;

FIGURE 6 is a sectional view, taken on the line 6—6 of FIGURE 3;

FIGURE 7 is a sectional view, taken on the line 7—7 of FIGURE 3;

FIGURE 8 is a top plan view thereof with the closure removed; and

FIGURE 9 is a top plan view thereof.

I claim:

The ornamental design for a decanter and closure therefor, as shown.
